CLAIM

The ornamental design for a car foot peg as shown and described.

DESCRIPTION

FIG. 1 is a top, front, right side perspective view of a car foot peg showing my new design;

FIG. 2 is bottom, rear, left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a second front elevation view, where the unclaimed mirror image is shown to be used as a pair.

The broken lines in FIG. 9 show a car foot peg depicting environmental structure and forms no part of the claimed design. The broken lines shown on the surface of the claimed design, depicts portion of a car foot peg that forms no part of the claimed design.
